UNITED STATES PATENT OFFICE.

LOREN W. WEBBER, OF MITCHELL, SOUTH DAKOTA.

BUTTON.

1,202,254.

Specification of Letters Patent.

Patented Oct. 24, 1916.

Application filed January 22, 1916. Serial No. 73,698.

To all whom it may concern:

Be it known that I, LOREN W. WEBBER, a citizen of the United States, residing at Mitchell, in the county of Davison and State 5 of South Dakota, have invented certain new and useful Improvements in Buttons, of which the following is a specification, reference being had to the accompanying drawings.

10 My invention relates to buttons for use on clothing, and particularly to a type of button which is at present used on cutaway coats, dress coats and other like garments where the two margins of the garment are 15 linked together instead of being overlapped and buttoned by a button passing through a button hole on one of the margins.

One object of my invention is the provision of a button which is so constructed that 20 the button may be either inserted through the button hole from the back or inside face of the flap of the garment, or have its shank inserted from the outer face of the garment and into engagement with the button hole 25 so that thereby the link connecting the button to the opposite flap of the garment may either pass across the outside face of the first flap or beneath the inside face thereof.

A further object is to provide a button of 30 the character described, the link of which may be engaged with a regular button on a coat, the head being arranged to engage the button hole in the manner above stated, the shank being so formed as to engage the margin 35 of the button hole and hold the button firmly in place as if it had been inserted from the inside of the garment.

Other objects will appear in the course 40 of the following description.

My invention is illustrated in the accompanying drawings, wherein:

Figure 1 is a view showing my invention applied to a coat; Fig. 2 is a sectional view of a coat through the button hole thereof, 45 and showing my improved button in one of its applications; Fig. 3 is a like view to Fig. 2, but showing the button in another of its applications; Fig. 4 is an inside face view of the button; Fig. 5 is an outside face view 50 thereof; Fig. 6 is a perspective detail view of the eye 14; Fig. 7 is a fragmentary view of a portion of a coat showing another manner of wearing a button; Fig. 8 is a view showing another manner of constructing the 55 button. In Fig. 3 I show an enlarged view of the button and in this figure, 10 design-

nates the head of the button and 11 the shank. This shank extends from the center of the button, then is bent to form a loop 12, this loop being carried outward beyond 60 the center of the button and toward the inner face of the button and then bent around to form an eye 13. This shank may either be formed of one piece of wire or suitable material, as in Fig. 3, or of two pieces of wire 65 as in Fig. 8. The shank, however, has the same operation and purpose in both cases. At the margin of the button on its inner face there is provided a semi-circular eye 14 which also forms a protuberance from the 70 inner face of the button. Attached to the shank at the eye 13 is a loop of chain or cord designated 15 which constitutes a flexible link.

In the application of the button to the 75 coat, the loop of the chain or cord 15 is engaged over the ordinary button 16 on the flap of the coat, though this chain or cord 15 may be attached directly to the face of the flap A. The former method, however, 80 is preferable. The opposite flap B is provided with the usual button hole with which ordinarily the button 16 engages but with which the button 10 is adapted to be engaged. Under certain circumstances, it is 85 desirable to insert the button 10 from the rear face of the flap B and in this case the button is carried beneath the rear face of the flap B, as in Figs. 3 and 7, and the link is 90 also carried beneath this rear face and then the button is inserted like an ordinary button through the button hole, with the head of the button upon the outside of the garment, the shank 11 entirely inside the garment, and the adjacent end of the link on 95 the inside face of the garment. Under certain other circumstances, however, it may be found desirable to dispose the link 15 entirely upon the outside face of the flap B, as 100 in Figs. 1 and 2, and in this case the shank 11 of the button is inserted through the button hole from the outside face of the garment and then the button is shifted laterally so that the eye 13 will engage against the inner face of the cloth while the inner face 105 of the button will engage against the outer face of the cloth. The link under these circumstances is carried from the eye 13 around the shank 11 where this shank joins the head of the button, and preferably the eye 14 is 110 made with a slight opening 14^a at one side through which the link may be passed into

the eye. This prevents any tendency of the link to unwind or otherwise become disengaged from its position looped around the junction of the shank with the button. It will be seen that the eye 14 constitutes a slight protuberance which spaces the head of the button from the coat sufficiently so as to permit the link to have free movement. The shank is of course to be made of slightly resilient material so that it will have somewhat the nature of a spring clamp. It is of course obvious that the button may be of any desired ornamental design and be of any suitable material or covered with cloth or silk as is the custom with buttons for use with evening clothes. The button, however, may be made of gold or other precious metal, if desired.

In Fig. 8 I show a slightly modified form 20 of button in which the shank 11^a is made of two wires which diverge at their point of engagement with the head 10^a. This shank is curved to form the loop 13^a, as previously described.

25 The uses and advantages of my improved button are many. When walking, if the weather is very warm, it is disagreeable to have the coat buttoned, yet it is also disagreeable to have it unbuttoned with the 30 sides flapping. Also most people like to place their hands in the coat pockets when walking, but this causes an uncomfortable tightness in the back of the coat. Men when dancing usually button the lower button 35 of the coat when as a matter of fact the body should have plenty of room to sway back and forth, but if on the other hand the coat was unbuttoned the skirts would fly in any direction. Likewise when sitting 40 down the coat has to be adjusted. These inconveniences are done away with by the use of my improved button which permits the coat to be loosened without however being entirely opened. Furthermore, the button 45 adds a dressy touch to the coat and can be removed when not in use.

It will, of course, be noted that my improved button may be attached to the garment by attaching the end of the link 15 50 thereto or be used as an auxiliary button by engaging the loop 15 around the button 16 and using the button 10 in the manner heretofore described.

Having described the invention, what I 55 claim is:

1. A button of the character described comprising a head, a shank formed to provide an eye spaced from the inner face of the head and forming a spring clamp in connection therewith, and a flexible link attached to said eye.

2. A button of the character described in-

cluding a head, a slightly resilient shank bent to provide a relatively large open loop disposed in a plane at right angles to the 65 plane of the inner face of the button, the extremity of the loop being bent to form an eye opposed to the inner face of the button, the eye thereby forming a resilient clamp coacting with the inner face of the button, 70 a flexible link attached to said eye, the inner face of the button outward of the eye and in line therewith being formed with a protuberance.

3. A button of the character described in- 75 cluding a head, a slightly resilient shank bent to provide a relatively large open loop disposed in a plane at right angles to the plane of the inner face of the button, the extremity of the loop being bent to form an 80 eye opposed to the inner face of the button, the eye thereby forming a resilient clamp coacting with the inner face of the button, a flexible link attached to said eye, the inner 85 face of the button outward of the eye and in line therewith being formed with a semi-circular eye, said eye being open at one point to permit the insertion of the link in the eye.

4. The combination with a garment hav- 90 ing opposed flaps, one of said flaps being provided with a button hole, of a flexible member attached to the other flap, and a button provided with a shank bent to provide an open loop, the extremity of the loop 95 being bent to provide an eye opposed to the inner face of the button and acting as a clamping member, said link being attached to the eye.

5. The combination with a garment hav- 100 ing opposed flaps, one of said flaps being provided with a button hole, of a flexible member attached to the other flap, and a button provided with a shank bent to provide an open loop, the extremity of the 105 loop being bent to provide an eye opposed to the inner face of the button and acting as a clamping member, said link being attached to the eye, and means being provided on the inner face of the button nearly opposite said eye for engaging the link.

6. A button of the character described comprising a head, a shank formed to provide an eye spaced from the inner face of the head, the shank being bent to embrace 115 the edge of a garment, and a flexible loop attached to said eye.

In testimony whereof I hereunto affix my signature in the presence of two witnesses.

LOREN W. WEBBER.
